UNITED STATES PATENT OFFICE.

LAURITZ SOPHUS HAASTED, OF DRAMMEN, NORWAY.

STOP BLOCK FOR RAILWAYS.

Application filed May 10, 1924. Serial No. 712,342.

To all whom it may concern:

Be it known that I, LAURITZ SOPHUS HAASTED, engineer, a subject of the King of Norway, residing at Drammen, Norway, have invented certain new and useful Improvements in Stop Blocks for Railways; and I do hereby declare the following to be a full, clear, and exact description of the invention, such as will enable others skilled in the art to which it appertains to make and use the same, reference being had to the accompanying drawings, and to letters or figures of reference marked theron, which form a part of this specification.

My invention relates to detachable stop blocks, adapted to be fastened to a rail for the purpose of preventing cars standing on a side track from leaving the same.

In the following the invention shall be described with reference to the accompanying drawings illustrating by way of example two executional forms of my improved stop block.

Figs. 1 and 2 are respectively a side view and an end view of an executional form of the stop block.

Figs. 3 and 4 are corresponding views of the other form. The stop block is made up of two separate members *a* and *b*, whose inner faces are formed so as to fit exactly about a rail as shown in the drawings.

In the form illustrated in Figs. 1 and 2 there are fastened to one of said members, that is, the member *a*, two or more bolts *d* provided with flat heads *e*, and the other member *b* of the stop block is provided with corresponding holes *f f*, having on one side slot shaped elongations *g*, *g*, of a width corresponding to the diameter of the bolt stems *d*.

Near their upper edges the members *a* and *b* are provided with corresponding elongated slots *h*, through which is slipped a handle ring *i*, serving also to keep the parts together when the stop block is detached.

Further the members *a* and *b* are provided with corresponding holes *j* for the insertion of a bolt provided with a locking device.

When the stop block is to be mounted on a rail the two members *a* and *b* are placed one on each side of the rail with the bolt heads *e* on the one registering with the corresponding holes *f* in the other member, whereupon the two parts are displaced longitudinally relatively to each other, the bolt

stems being moved into the slots *g*, thereby locking the two members *a* and *b* together by aid of the bolt heads *e* and thereby also clamping the lower parts of said members on the rail.

Finally the locking bolt is inserted through the two holes *j* now registering with each other, this bolt being preferably provided with locking means—preferably a control lock, in order to prevent the removal of the stop block by unauthorized persons.

The flatheaded bolts *d* may be replaced by other locking means. In Figures 3 and 4, each member *a'*, *b'* is provided at one end with a laterally extending tongue *m* bent to form a hook adapted to engage the outer face of the opposite member.

When the stop block is to be mounted on a rail the two members *a'*, *b'* are placed one on each side of the rail, whereupon the two members are displaced longitudinally relatively to each other, until the tongues *m* grip tightly about the edges of the members *a'*, and *b'* respectively and thereby clamping the lower parts of the members onto the rail.

Finally a locking bolt *j'* is inserted through the two holes *j* now in register with each other, this bolt being preferably provided with locking means, preferably a control lock *n*.

Instead of having the members *a*, *b* or *a'*, *b'* interconnected by a handle ring these parts may also be interconnected by means of a bolt *k*, arranged longitudinally to the stop block (see Figs. 3 and 4) the two parts *a'*, *b'* being swung about this bolt, when the stop block is to be attached to the rail or detached from the same. This bolt *k* also forms a guide for the relative longitudinal displacements of the parts *a'*, *b'*, and is provided with a projection or stop *g'* limiting said longitudinal displacement.

Claims:

1. A stop block for railways comprising two rail clamping members, means connecting said members to permit relative longitudinal movement thereof, and tongues on the ends of said members, operable by a relative longitudinal movement of the latter, adapted to effect an interlocking of said members when the latter register with each other.

2. A stop block for railways comprising two clamping members, means connecting

100

105

110

said members to permit relative longitudinal movement thereof, tongues on the ends of said members, operable by a relative longitudinal movement of the latter, adapted to effect an interlocking of said members, and a bolt adapted to be projected through said members to maintain them in locked relation when in register with each other.

3. A stop block for railways comprising
10 two clamping plates having lower portions to grip the sides of a rail, a bolt connecting said members above the gripping portion to permit relative longitudinal movement of said plates, and a laterally extending tongue
15 formed on each plate for locking engagement with the edge of the opposing plate when said plates are moved into operative position.

4. A stop block for railways comprising
20 two clamping plates having lower portions to grip the sides of a rail, a bolt connecting said members above the gripping portion to permit relative longitudinal movement of said plates, a laterally extending tongue
25 formed on each plate for locking engage-

ment with the edge of the opposing plate 30 when said plates are moved into operative position, and a bolt adapted to project through the plates to prevent disengagement of the tongues.

5. A stop block for railways comprising 35 two clamping plates having lower inner face portions to grip the sides of a rail, a bolt fixed in the upper portion of one plate and extending longitudinally thereof, and on which the other plate is movable longitudinally, means to limit the relative longitudinal movement of said plates, a hook formed on one end of each plate adapted to engage the opposing edge of the opposite plate, and a bolt passing through said plates 40 to prevent relative longitudinal movement thereof.

In testimony that I claim the foregoing as my invention, I have signed my name in presence of two subscribing witnesses.

LAURITZ SOPHUS HAASTED.
